(57) **CLAIM**

The ornamental design for a nail setter, as shown and described.

DESCRIPTION

FIG. 1 is a front perspective view of a nail setter, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of detail 8 in FIG. 1;

FIG. 9 is an enlarged view of detail 9 in FIG. 1;

FIG. 10 is an enlarged view of detail 10 in FIG. 2; and,

FIG. 11 is an enlarged view of detail 11 in FIG. 2.

The dashed broken lines in the figures are for the purposes of illustrating portions of the nail setter that form no part of the claimed design.

The dash-dot-dash broken lines are for notating enlarged views and form no part of the claimed design.

1 Claim, 11 Drawing Sheets
